MARINE V-DRIVE

William B. Herbert, 111 Yantacaw Brook Road,
Upper Montclair, N.J. 07043

Filed Oct. 21, 1965, Ser. No. 87,669

Term of patent 14 years

(Cl. D55—1)

Fig. 1

Fig. 4

FIG. 1 is a top plan view of the marine V-drive;
 FIG. 2 is a side elevational view of the marine V-drive;
 FIG. 3 is an elevational view of one end of the marine V-drive, as viewed from the left side of FIG. 2, and

FIG. 4 is an elevational view of the other end of the marine V-drive, as viewed from the right side of FIG. 2.

I claim:

The ornamental design for a marine V-drive, substantially as shown.
